CLAIM

The ornamental design for a mounting bracket, as shown and described.

DESCRIPTION

FIG. 1 is a top perspective view of a mounting bracket, showing my new design;

FIG. 2 is a bottom perspective view thereof;

FIG. 3 is a rear perspective view thereof;

FIG. 4 is a front view thereof;

FIG. 5 is a left side view thereof;

FIG. 6 is a right side view thereof;

FIG. 7 is a rear view thereof;

FIG. 8 is a top view thereof; and,

FIG. 9 is a bottom view thereof.

The uniformly dashed lines shown in the drawings illustrate portions of the mounting bracket which form no part of the claimed design.

1 Claim, 4 Drawing Sheets(56)
